EMIL C. LOETSCHER, OF DUBUQUE, IOWA.

FOUNTAIN PEN, MEDICINE DROPPER, AND THE LIKE.

Application filed November 30, 1926. Serial No. 151,685.

The principal object of this invention is to provide the compressible filling or refilling bulb of a fountain pen, medicine dropper, syringe, or the like, with an improved form 5 of diaphragm check valve to enable the implement to be filled to capacity through successive compressions of the bulb.

A second object of the invention is to improve the mode of attaching such a bulb to 10 the body of the implement.

A third object of the invention is to provide means for holding the valve positively seated, while at the same time guarding the bulb against undesired compression.

15 With these and still further objects in view, reference will be had to the accompanying drawing forming a part of this specification, wherein like numerals of reference designate corresponding parts throughout the several 20 views, in which:

Fig. 1 is a longitudinal vertical sectional view taken through a fountain pen with the invention applied.

Fig. 2 is an enlarged detail view in longitudinal section of the bulb end of the fountain pen, or other implement, and

Fig. 3 is a longitudinal vertical sectional view of a modified form of bulb, illustrated with a fragment of the guard cap juxtaposed.

30 Referring to the drawing, reference numeral 1 designates the barrel or liquid reservoir of a fountain pen, medicine dropper, syringe, or similar implement, into which liquid is to be drawn through the agency of a compressible bulb. The reservoir barrel 1 itself, or an attached pen nib or nozzle carrying attachment 2 is provided with an admission port or passage 3 of a capillary nature, which, in the case of a fountain pen, not only leads the 35 ink into the reservoir 1 in filling or in refilling, but also serves in writing to feed the pen nib 4 with ink from the barrel.

40 Into the opposite end of the barrel is inserted a plug 5 with a bore 6 of the same diameter as the passageway 3. The threads 7 on the plug engage internal screw threads within the reservoir. When the plug 5 is in place, a portion thereof extends beyond the end of the reservoir 1 exposing the threads 7 45 of that portion for the purpose of receiving the guard cap 9 which threads thereon. The projecting portion of the plug 5 is formed with a reduced portion or neck 10 exteriorly threaded to receive an interiorly threaded collar or nut 12 which is located within the compressible bulb 14, so that when the nut 12 is

screwed into place, the integrally formed inwardly extending flange 15 of the bulb will be firmly gripped between the shoulder 16 of the plug 5 and said nut 12, forming an effective 60 liquid tight joint, as well as effectively holding the bulb 14 in position.

The bulb 14 in the preferred form, is slightly contracted toward one end to form a neck 15, shoulder 16, and rounded enlarged head 17, the latter being provided with a vent orifice 18. Over the head 17 is placed a thin rubber cap 19, provided with reinforced edge 20 less elastic than the body portion 19, and this marginal portion 20 being of less diameter than the portion 19, fits behind the shoulder 16 at the neck portion 15 of the bulb, closing the vent orifice 18 against admission of air, but permitting egress of air from the orifice 18 between the bulb head 17 and cap portion 70 19, beneath the marginal portion 20 of the cap to the atmosphere. The cap 9 has its closed end 21 interiorly conforming with the contour of the closed end 17 of the bulb and cap 19, so as to force the cap 19 against the 80 bulb end 17 to positively seat the valve and close said orifice 18 when the pen is in use.

The bulb is made of flexible rubber or the like, while the other parts, with the exception of the pen nib, are of hard rubber, celluloid, 85 bakelite or the like, with the barrel preferably transparent to expose the liquid within the reservoir.

In use, when it is desired to fill the reservoir 1 of the implement, the cap 9 is removed, 90 and the bulb 14 compressed to expel the air therefrom through the core 6 of the plug 5, displacing the air within the reservoir 1 and forcing it out through the liquid admission port or passage 3. There being no liquid 95 within these parts initially, the air will take the described course in preference to the path of greater resistance through the vent port 18. With the air so exhausted, or partially so, the end of the implement with the admission port or passage 3 is submerged in the liquid to be drawn into the reservoir 1, whereupon the bulb is released and upon expanding to normal shape permits atmospheric pressure to force the liquid through said port 3 into the 100 reservoir 1 of the implement. The fluid capacity of the bulb 14 is considerably less than that of the barrel 1, so that it requires repeated operations to fill the reservoir 1 to capacity, 105 and in the second and successive operations, 110 the action is different from that of the first described operation, as follows: Upon the

successive compressions of the bulb 14, with the admission port end still submerged in the supply liquid, the air within the bulb will not pass through the port 6 nor through the admission port 3, but will take the less resistive course through the vent orifice 18, passing between the bulb head 17 and cap 19 and beneath the rim 20 to the atmosphere. The reason the course through the vent orifice 18 offers less resistance is because the passage 6 in the plug 5 not only offers some resistance to the passage of the air from the bulb in that direction, but because the capillary nature of the admission port or passage 3 will permit the liquid to pass only very slowly through the same, thereby virtually forming a liquid seal against the exhaustion of the air through this port or passage 3 when liquid is present in the reservoir. Thus the liquid capacity of the implement is not controlled by that of the bulb 14, since it is only necessary to repeat the operations of the bulb in order to fill the reservoir 1 to capacity whatever its size may be. As soon as the liquid has completely filled the reservoir 1, upon the next compression of the bulb, the remaining air will be expelled therefrom through the vent 18 and the tendency will be to draw the liquid through the restricted passage 6, but owing to its capillary nature, the flow therethrough of the liquid will be resisted more than that of the air that went before and accordingly, the bulb will remain compressed for a longer period of time than before, thereby giving a signal or indication that the reservoir is completely filled with liquid. To use the implement, it is not necessary to apply the cap, but in some applications it is highly desirable, as in the case of a fountain pen, to protect the bulb while the pen is contained within the pocket, and when applied, its closed end portion 21 positively holds the valve portion to seat over the vent orifice 18.

In the case of the modified form of Fig. 3, the bulb 14' is attached by means of the nut 12' and flange 15' as in the preferred form, but is unrestricted throughout its length, though formed with a rounded closed end. In this form, the venting of the bulb is through one or more side orifices 18', these being closed by an incircling elastic rubber ring 19', which is positively held to its seat by pressure of the side portion 21' of the cap 9' when the latter is applied.

55 What is claimed:—

1. The combination with a liquid reservoir having an opening at one end for the entry and egress of the liquid, of a resilient bulb at the opposite end for exhausting the air from the reservoir and having a vent opening, and a flexible diaphragm surrounding a portion of the bulb and covering said vent opening and permitting passage of air therethrough in one direction only.

65 2. The combination with a liquid reservoir

having an opening at one end for the entry and egress of the liquid, of a resilient bulb at the opposite end of the reservoir for exhausting the air from the reservoir and having a vent opening, a flexible diaphragm surrounding a portion of the bulb and covering said vent opening and permitting passage of air in one direction only through said vent opening, said diaphragm elastically gripping said bulb. 75

3. The combination with a liquid reservoir having an opening at one end for the entry and egress of the liquid, of a resilient bulb at the opposite end of the reservoir for exhausting the air from the reservoir and having a vent opening, of a flexible diaphragm surrounding a portion of the bulb and covering said vent opening and permitting passage of air therethrough in one direction only, and a cap member for said reservoir arranged to engage and positively seat said diaphragm over said vent opening. 80

4. The combination with a liquid reservoir having restricted openings at both ends, one of which is a capillary opening, of a resilient bulb applied to the reservoir at the end opposite the capillary opening, said bulb having a vent opening, a flexible diaphragm elastically inclosing the portion of the bulb adjacent the vent opening, and a guard cap adapted to be applied to said reservoir and when so applied to engage said diaphragm to positively seat the same. 85

5. The combination with a body member having a reduced threaded portion forming a shoulder, of a resilient bulb having an inwardly extending flange, and a threaded nut within said bulb threaded on said reduced threaded portion and confining said flange between itself and said shoulder. 100

6. The combination with an exteriorly screw threaded body member having a reduced threaded neck portion forming a shoulder, of a resilient bulb having a vent opening and an inwardly extending flange, a threaded nut within said bulb threaded on said neck and confining said flange between itself and said shoulder, a diaphragm check valve member inclosing the portion of said bulb having the vent opening, and an internally threaded cap on said body member positively seating said diaphragm upon said vent opening. 110

7. In combination, a bulb having a vent opening, a flexible diaphragm encircling a portion of said bulb and inclosing said vent opening. 115

8. In combination, a bulb having a vent opening, of a cap-shaped flexible diaphragm inclosing one end of the bulb and said vent opening and being retained in position by its own elasticity. 125

9. In combination, a bulb having an enlarged end with a vent opening, a cap-shaped flexible diaphragm inclosing said enlarged end of the bulb and closing said vent opening 130

and being retained in position by its own elasticity.

10. In combination, a bulb having a neck portion and an enlarged head portion provided with a vent opening, a flexible cap member inclosing said head portion and vent opening, the marginal portion of the cap being of less diameter than the head portion.

11. The combination with a liquid reservoir having capillary openings at each end, a resilient filling bulb secured to one end of the reservoir and having its interior communicating with the interior of the reservoir through one of said openings, said bulb having a vent opening, and a check valve connected to the bulb and cooperating with said vent opening to permit passage of air therethrough in one direction only.

12. The combination with a liquid reservoir, of a resilient filling bulb connected there-

to and having less capacity than the reservoir, said bulb having a vent opening, a check valve connected to the bulb and cooperating with said vent opening to permit the passage of air therethrough in one direction only, and means 25 for causing the bulb to remain compressed longer after the reservoir is filled, than while it is filling.

13. The combination with a tubular liquid reservoir, of a resilient filling bulb connected 30 to one end of the reservoir, and having its interior communicating with the interior of the reservoir, said bulb having a vent opening, and a check valve connected to the bulb and cooperating with the vent opening to permit 35 the passage of air therethrough in one direction only.

In testimony whereof I affix my signature.

EMIL C. LOETSCHER.
